UNITED STATES PATENT OFFICE.

FRANK H. STEWART, OF ELKINS PARK, PENNSYLVANIA.

WOVEN FABRIC.

1,368,214.

Specification of Letters Patent.

Patented Feb. 8, 1921.

Application filed June 9, 1920. Serial No. 387,584.

To all whom it may concern:

Be it known that I, FRANK H. STEWART, a citizen of the United States, residing in Elkins Park, Pennsylvania, have invented certain Improvements in Woven Fabrics, of which the following is a specification.

My present invention relates to woven fabrics for use in the manufacture of automobile, and other, tires for the purpose of sup- 10 plying a fabric base about which the rubber or similar resilient material, is formed. This invention is similar to that forming the subject matter of my application for United States Letters Patent filed February 3, 1920, 15 Serial No. 355,972, and consists of certain improvements in and additions to the fabric shown and described in that application.

My present invention is illustrated in the accompanying drawings, in which—

20 Figure 1 is a diagrammatic view showing, in transverse section, the contour of fabric woven in accordance with my invention;

Fig. 2 is a similar view showing a similar fabric but of modified form;

25 Fig. 3 is a face view of the take-up roll employed in connection with a loom adapted to weave fabrics of the transverse contour shown in Figs. 1 and 2, and

Fig. 4 is a face view, on an exaggerated scale, and diagrammatic, of a flat projection of a piece of fabric woven in accordance with my invention.

Fabrics woven in accordance with the invention set forth in my before noted application are especially adapted for use in connection with tires for the reason that they are woven in such manner that they are inherently possessed of both transverse and longitudinal curvature and therefore re- 35 quire no distortion to accord with the transverse and longitudinal curve of the tire. The objects of my present invention are to so weave the fabric that it will be reinforced at its edges and, if desired, centrally of its width. The first object I accomplish, as shown in Figs. 1 and 2, by so weaving the fabric *a* that its edges *b*, *b* will fold back, and the second object I may accomplish, as shown in Fig. 2, by weaving the central por- 45 tion *c* of the fabric *a* that it is of double thickness. In Fig. 4 is illustrated, diagrammatically, the manner in which the warp and weft threads are interwoven to accom- 50 plish the desired results.

55 Basically, the arrangement and disposi-

tion of threads is the same as in the fabric of my previous application, the present invention consisting purely in certain amplifications thereof and additions thereto. Referring to Fig. 4 it will be seen that the fabric comprises groups 1, 2, 3 and 4 of warp threads, weft threads 5, 6, 7 and 7^a, loop locking threads 5^a and 6^a, and where desired, supplementary weft threads 8, 8^a and 9.

The weft threads 5, 6 and 7 are interwoven with the warp threads in the same manner as is shown in my pending application, as is also the weft thread 7^a with the exception that said thread 7^a is inserted from the opposite side of the fabric from the side from which the thread 7 is inserted. Briefly stated, the weft threads 5, 6, 7 and 7^a are inserted in serial order, for to-and-fro runs through successive sheds of the warp threads and for different transverse distances, that is to say, the weft thread 5 is interwoven only with the warp threads of the group 1 while the weft thread 6 is interwoven with the warp threads of the groups 1 and 2 and the weft threads 7 and 7^a are interwoven with all of the warp threads taking in the groups 1, 2, 3 and 4.

As before, the warp threads of all of the various groups differ in length for the purpose of creating and maintaining the proper transverse and longitudinal curvature in the finished fabric. The threads of the groups 2 are progressively shorter than the threads of the group 1 and the threads of the groups 3 are again progressively shorter than the threads of the groups 2. In order, however, that the edges *b* of the fabric *a* (Figs. 1 and 2) may fold back, the threads of the groups 4 are progressively longer than the threads of the groups 3. The dividing lines between the groups 3 and 4, consequently, are the points of occurrence of the shortest warp threads and, as a result, these are the points of greatest contraction in the finished fabric, and provide the lines on which the edges of the fabric fold back.

In order to agree with the increased length of warp threads at the edges of the fabric it is desirable that extra interwoven weft filling be provided in connection with the threads of the groups 4. Two methods are illustrated by which this may be done. The loops 10 at the end of each to-and-fro run of the weft threads 7 and 7^a may be of such length that they may be reinserted in 110

the next shed of the warp threads, engaging only with the threads of the groups 4, or supplementary weft threads 8 and 8^a may be employed, these threads being inserted, 5 at intervals, to form to-and-fro runs engaging only with the threads of the groups 4. It is of course, understood, that extended loops 10 are only formed and reinserted or runs of the weft threads 8 and 8^a only 10 occur at such intervals as prove to be necessary to properly accord with the length of the warp threads of the groups 4 and to provide the filling for the fabric of desired form and contour.

15 When it is desired to form the central reinforcement *c* (Fig. 2) I make use of the supplementary weft thread 9. This thread differs from the other weft threads in as much as it is interwoven in every shed of 20 the warp threads rather than in rotation with the other weft threads. The traverse of this thread is only such portion of the central section of the web as it is desired to reinforce and the to-and-fro runs overlie 25 the corresponding to-and-fro runs of the main weft threads, thereby forming the double thickness of fabric.

Reference to Fig. 3 will illustrate the manner in which the take-up roll *x* of the 30 loom is formed to properly coördinate with the transverse and longitudinal curve of the fabric. This roll *x* is, preferably, of substantially globular shape with expanded flaring ends, which ends serve to accommodate 35 the turned back edges of the fabric.

It must be particularly understood that Fig. 4 is purely diagrammatic and, in addition, represents a flat projection of the fabric. While it illustrates, accurately, the 40 tails of the weave the effect is not that which is given by the fabric itself. The outstanding feature of difference is that, while the drawing shows, at the sides of the fabric, relatively long stretches of warp threads 45 with which no wefts are interwoven, this effect is not present in the actual fabric. These stretches of warp threads are caused by the flat projection of the fabric in the same way that a map of the world, on 50 Mercator's Projection, greatly distorts the regions adjacent the poles. In the actual fabric, owing to the varying lengths of the warp threads, the weft threads occupy the full space and are beaten up close to one 55 another, no gaps being present. This point must be thoroughly understood in order that

no erroneous idea be formed regarding the invention.

I claim:

1. A woven fabric comprising a set of 60 warp threads and a continuous weft-forming thread interwoven therewith, said weft-forming thread passing forward and backward in the same shed of the warp threads to form a to-and-fro run therein, said to-and-fro run being of greater length than the width of the fabric and having its excess length returned through the adjacent 65 shed of the warp threads to form a to-and-fro run in said adjacent shed. 70

2. A woven fabric comprising a set of warp threads and a plurality of continuous weft forming threads interwoven therewith, one of said weft-forming threads being interwoven with all of said warp threads and 75 another of said weft forming threads being interwoven only with the warp threads disposed adjacent to an edge of the fabric, and each of said weft forming threads, where interwoven with said warp threads, 80 passing forward and backward in the same shed of said warp threads to form a to-and-fro run therein.

3. A woven fabric comprising a set of warp threads and a plurality of continuous 85 weft-forming threads interwoven therewith, one of said weft forming threads being interwoven with all of said warp threads, another of said weft-forming threads being interwoven only with the warp threads disposed adjacent to an edge of the fabric, 90 and another of said weft forming threads being interwoven only with the warp threads disposed adjacent to the opposite edge of the fabric, and each of said weft-forming threads, where interwoven with said warp threads, passing forward and 95 backward in the same shed of said warp threads to form a to-and-fro run therein. 100

4. A woven fabric comprising a set of warp threads and a plurality of continuous weft forming threads interwoven therewith, said weft forming threads passing to and fro, in serial order and for different distances, through successive sheds of the warp 105 threads, and a supplementary weft thread passing to and fro through each shed of warp threads and overlying the weft thread therein.

In testimony whereof I have signed my 110 name to this specification.

FRANK H. STEWART.
